UNITED STATES PATENT OFFICE.

JAMES H. RICKER, OF ST. LOUIS, MISSOURI, ASSIGNOR OF ONE-HALF TO HENRY W. EDDY, OF ST. LOUIS, MISSOURI.

LASTING-TACK PULLER.

1,314,702.

Specification of Letters Patent.

Patented Sept. 2, 1919.

Application filed February 25, 1918. Serial No. 219,085.

To all whom it may concern:

Be it known that I, JAMES H. RICKER, a citizen of the United States, residing at St. Louis, in the State of Missouri, have invented certain new and useful Improvements in Lasting-Tack Pullers, of which the following is a specification containing a full, clear, and exact description, reference being had to the accompanying drawings, forming 10 a part hereof.

My invention relates to an improved machine for pulling the lasting tacks which temporarily hold the welt shoe upper and insole on the last, and the invention consists 15 in the novel construction and combination of parts hereinafter fully described, and substantially as pointed out in the claim found at the end of the descriptive portion of this specification.

20 The object of my present invention is to improve upon the machine which is shown and described in my former U. S. Patent No. 1,004,081, granted to me under date of September 26, 1911, for a lasting-tack 25 puller; whereby the machine will be more complete and efficient, as well as being mounted upon its own portable base and standard carrying its independent motor, thereby permitting the machine to be readily moved whenever required.

In the drawings,

Figure 1 is a front elevation of a lasting-tack puller of my improved construction.

Fig. 2 is an enlarged detail cross-section 35 of the revoluble head of the tack puller, taken on the line 2-2 of Fig. 1.

Fig. 3 is a detail side-elevation of one of the combination rotary jaw and comb slides, removed from the head.

40 Fig. 4 is an end view of the slide shown in Fig. 3, looking at same in the direction indicated by the arrows 4-4 of Fig. 3.

Fig. 5 is a top plan-view of the bearing and cam, in which the revoluble head is to 45 be mounted.

Fig. 6 is a cross-section of the revoluble head, the section being taken on the line 6-6 of Fig. 7, and

50 Fig. 7 is a side-elevation of the revoluble head, detached from the bearing and cam.

My improved tack puller is adapted to operate immediately in advance of the needle of the inseam sewing machine (not shown), to positively and accurately engage 55 and pull all of the tacks, and thus leave the

work free to be engaged by the needle of the inseamer.

An important portion of my invention is the improved revoluble head constructed in two parts which rotate together, and one of which parts has a fixed circular jaw which co-operates with the other part, which latter is made in sections carrying rotating jaws which move axially of the head to clamp the tacks between said fixed circular jaw and 60 said rotating sectional jaws, and pull said tacks as the entire head rotates, and which sectional jaws finally release and discharge the pulled tacks; said sections also carrying each a series of curved comb-teeth which 65 engage and pull any tacks which the carelessness of the operator may have caused the said jaws to miss during the operation of the machine.

70 The numeral 1 designates a standard rising from a suitable base-plate 2 and having fixed upon its upper end a combined head-bearing and cam 3.

This combined device I shall hereinafter 75 designate the head-bearing of the machine.

80 Mounted to rotate in the said head-bearing 3 is a horizontal jaw-head 4 having a plain end 5 on which is fixed a suitable pulley 6, by means of which power may be imparted to the said head from any desired 85 source, to rotate the latter in the direction indicated by the arrow in Fig. 2.

Arranged to slide freely upon the said 90 jaw-head 4 are a series of plates 7, which are guided by the walls of longitudinal 95 grooves 8 formed in the periphery of the head, the said plates being held in position in the said grooves by contact with the interior of the said head-bearing 3, whose bore their outer surfaces are curved to fit at the 95 point of contact with the said bore.

The said head-bearing 3 is so fixed upon the upper end of the said standard 1 that (as shown in Figs. 1 and 5) the right-hand end or edge of said bearing is the reverse in contour of the left-hand edge of same; that is, there is a high cam-surface 9 and a low cam-surface 9' on the right-hand edge, and a low cam-surface 9'' on the opposite edge of said bearing directly opposite (and the reverse of 100 the shape of) the said high cam-surface 9, while there is also a high cam-surface 9''' directly opposite in a horizontal plane the said low cam-surface 9'; and the upper edges of the cam-surfaces at the right-hand 110

- end of the bearing are in vertical alinement with the lower edges of the same cam-surface, and this is also true of the cam-surfaces at the left-hand of the said bearing 3.
- 5 Formed integral with or attached to the outer surface of each of the said sliding plates 7 is a cam-lug 10 and a horizontal series of hooks or comb-teeth 10^a, which teeth are located between the said cam-lug and the 10 left-hand end of the said plates, on which is formed or attached a segmental jaw 11, the outer face of which is provided with radial or other form of corrugations or serrations 12, to clamp the tacks to be pulled 15 between themselves and the adjacent surface of a circular jaw or disk 14 which is fixed or formed upon the end of the said jaw-head 4 that is opposite that on which the said wheel or pulley 6 is fixed.
- 20 The said cam-lugs 10 engage the cam-surfaces on one edge of the said head-bearing 3, to move the said sliding plates 7 in one direction, and suitable rollers 10^b are mounted on the plates to engage the cam-surfaces 25 on the edge thereof which is opposite the edge engaged by the said cam-lugs and move the plates in an opposite direction.
- 25 A suitable portable motor, which is an electric motor 15 in the present illustration 30 of my invention, is mounted upon the horizontal arm of a bracket or platform 16 having a sleeve 17 mounted to slide vertically on the standard 1 and adjustably held in position by the set-screw 18.
- 35 Fixed upon the armature shaft of the said motor 15 is a common pulley 19 which is engaged by any common form of flexible belt 20, through which the power of said motor is transmitted to the pulley 6 of the said jaw-head 4, whereby the motor and the tack-pulling machine will be combined to form 40 an independent unit, which can be bodily moved from place to place intact.
- 45 The operation is as follows:
- The jaw-head 4 is rotated within the said head-bearing 3, carrying the said plates 7 with said jaw-head; and during such rotation the said plates are reciprocated in such a manner that the segmental-jaws 11 are 50 correspondingly moved toward and from the said circular jaw 14, which action is brought about by the engagement of the said cam-lugs 10 and the said rollers 10^b of the plates with the cam-surfaces upon the opposite edges of the said head-bearing, the said 55 cam-surfaces being so disposed that when one of the said jaws 11 moves into position opposite the lowermost portion of said circular jaw the cam-lug 10 of the particular 60 plate which carries that particular jaw 11 will come in contact with the high cam-surface 9^{'''} at the bottom of the said head-bearing to force this particular jaw 11 toward

the lowermost portion of the said circular jaw 14, and this action clamps or engages the 65 head of the lasting tacks which are seated in the last to hold certain parts of the shoe thereon, and which last is held in position immediately beneath the pulling machine, or in such position as that the parts of the 70 shoe are readily engaged by the needle of the inseamer; the said comb-teeth 10^a engaging and pulling any tacks which may be missed by the said jaws.

The tacks, after being pulled, are clamped 75 between the corrugated face of the segmental jaws 11 and the circular jaw 14, and upon and between the said comb-teeth, and are held in this position and carried around until the 80 said cam-lugs 10 pass the said high-cam surface 9^{'''} of the said head-bearing and the said segmental jaws are released by the sliding movement of the said plates which carry said jaws, which releases the tacks pulled by the said jaws, the tacks which have been 85 pulled by the said comb-teeth 10^a being discharged as soon as pulled.

The operations just described take place very rapidly, and occur immediately preceding the sewing of the inseam between the 90 shoe upper and insole, or between the upper, insole and welt.

The operations very positively and quickly remove the lasting-tacks, and as all of the tacks are removed there is no danger of 95 breaking the needle by engagement with a tack.

The needle of the inseam sewing machine feeds the work along, and the tacks are pulled immediately in front of the point where 100 the needle engages the work, and thus as all tacks are removed the work is left in perfect condition to be engaged by the needle, and the sewing operation is readily accomplished around the toe of the last without leaving 105 any fullness of the upper at this particular point.

I claim:

A lasting-tack puller, comprising a solid rotary jaw-head having a circular-jaw fixed 110 thereon, a series of plates mounted to slide longitudinally upon said head and provided with segmental-jaws which clamp the tacks between themselves and said circular-jaw; and comb-teeth carried by said plates adjacent 115 said segmental-jaws and moving therewith, to pull the tacks that are missed by said jaws.

In testimony whereof I have signed my name to this specification in presence of two 120 subscribing witnesses.

JAMES H. RICKER.
